(57) **CLAIM**

The ornamental design for a combined golf club brush and ball marker, as shown and described.

Jan. 6, 2010 (EM) 001654427

DESCRIPTION

(51) **LOC (10) Cl.** **21-02**

FIG. 1 is a top, front, side perspective view of a combined golf club brush and ball marker showing my new design;

(52) **U.S. Cl.**

FIG. 2 is an exploded top, front, side perspective view thereof;
FIG. 3 is a top plan view thereof, with the ball marker omitted
for clarity of illustration only;

USPC **D21/795**; D4/116; D4/121; D4/129

FIG. 4 is a left side, bottom perspective view of the design as
shown in FIG. 3;

(58) **Field of Classification Search**

FIG. 5 is a bottom plan view of the design as shown in FIG. 3;
FIG. 6 is a bottom, front perspective view of the design as
shown in FIG. 3; and,

USPC D4/116, 121, 129, 135; D21/793, 795;

FIG. 7 is a bottom, rear perspective view of the design as
shown in FIG. 3.

15/105, 159.1, 160, 191.1-193;
473/285, 286, 406, 408

The entire oval area shown in broken lines in FIGS. 1-3
illustrates a portion of the combined golf club brush and ball
marker that forms no part of the claimed design.

See application file for complete search history.
